HERBERT B. POLLEYS, OF NEW HAVEN CONNECTICUT, ASSIGNOR TO NATIONAL INDIA
BUBBER COMPANY, OF BRISTOL, RHODE ISLAND, A CORPORATION OF RHODE ISLAND

CEMENT APPLYING MACHINE

Application filed May 19, 1928. Serial No. 279,040.

The invention disclosed herein has for its purpose the application of cement to the uppers and soles of shoes so as to provide sufficient adherence for rubber strips and/or soles to be applied thereto.

It has been the practice in applying cement to shoes, especially canvas shoes, to use a brush and apply the cement manually. This method of application requires skilled workers who even though highly trained do not consistently apply the cement in a satisfactory manner since it usually has a wavy line and the band is so broad that it extends above the edge of the rubber strip, usually known as the foxing, which is applied along the lower edge of the upper or canvas shoe.

It is an object of this invention to provide means for applying such a band of cement so that it will have a straight edge and will have a bead at its edge where it is most likely that the foxing will be pulled loose.

The machine of this invention also provides means for applying cement to the bottom of the upper to which the sole may be applied. Another object is to provide a support for a shoe to which the cement is being applied which support is adjustable relative to the cement applying means.

Still another object is to provide means for removing excess cement from the bottom of the shoe.

Other objects of the invention will appear from the detailed description which follows.

In applicant's Patent No. 1,559,367 granted Oct. 27, 1925, there is disclosed a machine for applying cement to a shoe and in applicant's copending application Serial No. 179,772, filed March 31, 1927, there is disclosed another machine for applying cement to a shoe and his invention is an improvement thereon.

A preferred embodiment of the invention is disclosed in the drawings in which:

Fig. 1 is a side elevation of the invention.

Fig. 2 is a view taken on line 2—2 of Fig. 1, some parts of the machine being omitted for clearness.

Fig. 3 is a detailed view of the brush for

removing excess cement from the bottom of the shoe.

Fig. 4 is a sectional view on the line 4—4 of Fig. 2.

Fig. 5 is a detailed view, in the direction 55 of the arrow A, Fig. 1, showing the limiting device for limiting the extent of adjustment of the table.

Fig. 6 is a detail view of the means for applying a bead of cement to the shoe upper.

In the drawing there is provided a stand 1 having a top 2 to which the base member 3 is fastened by bolts 4. A switch box 6 is fastened by means of screws 5 to the base member 3. The switch box controls a motor, not shown, which drives belt 7 over the pulley 8 mounted on shaft 9 which is journaled in bearings 10—10. The pulley and belt are provided with the guard 11.

To the shaft 9 is fixed worm 11 which 70 drives worm wheel 12 mounted on shaft 13 which is journaled in bearings 15, 16 and 17. To the upper end of shaft 13 is fixed the cement applying disk 18. The cement applying disk has a depending sleeve 19 75 which extends into well 20 in the disk casing 21. The purpose of the flange 19 is to prevent cement from flowing from disk 18 into bearing 17.

The disk casing 21 is provided with cover 80 22 which has a cement inlet 23 integral therewith. Fitting into the cement inlet 23 is a valved conduit 24 leading from the cement tank 25 which is supported upon a bracket 251 carried by rods 252 which are 85 connected at the lower ends to the base member 3.

Cover 22 is hingedly mounted upon the disk casing 21 by pin 26 and is held in a closed position by bolt and thumb screw 27. 90 Cover 22 does not extend over the entire surface of the cement disk 18 but is cut away as shown at 221 so as to expose a portion of the cement applying disk.

On the cut-away portion of the cover 22 95 is mounted a scraper 28, the lower edge 30 of which contacts with the upper surface of disk 18. Scraper 28 is held on cover 22 by screws 29.

Underneath disk 18 is fastened, by means 100

of screws 32, a dam 31, the upper edge 33 of which contacts with the lower side of disk 18. In the upper edge of dam 31 a slot 34 is provided which is in register with a slot 35 formed in the surface of the cement disk casing just beneath the disk 18.

The scraper 28 serves to prevent any cement from passing out of the casing 21 on the upper surface of the disk, and causes the cement to back up and flow over the edge of disk 18 into the slot 35 from which the cement is carried on the lower surface of the disk out through slot 34 in the dam member 31. The dam member 31 serves to limit the amount of cement carried on the lower surface of the disk.

Beneath the disk 18 and adjacent the dam 31 is another scraper 36 which has for its purpose to direct the cement, which is on the lower surface of the disk, to the edge of the disk.

Immediately beneath the front edge of the disk 18 is positioned the brush 37 (Fig. 2) which brush is carried in spring clips 38 on the end of arm 39 which is pivoted by the pin 40 on bracket 401 of member 70. An adjusting screw 41 is threaded into aperture 42 in the end of arm 39 distant from the brush. A spring 43 surrounds the shaft 30 of screw 41 which serves to hold the screw from free rotation. The end of adjusting screw 41 contacts with stop member 44 (Fig. 1) which is pivotally mounted at 45 in the frame of the machine. A spring 46 is connected at one end to stop member 44 and is connected with the frame at the other end. Spring 46 serves to hold stop member 44 rotated into the position shown in Fig. 1, the rotation of the stop member 44 being limited by a pin (not shown) which is mounted in the frame. The end 47 of lever 39 has spring 48 connected thereto, which spring is connected at its other extremity to the cement disk casing 21. The spring 48 serves to rotate the arm 39 about its pivot 40 so as to move the brush 37 through aperture 49 in table 50 near to the disk 18. The extent of the rotation of arm 39 caused by spring 48 is adjustably limited by screw 41 contacting with the stop 44.

Another brush 51 extends up through aperture 52 in table 50 in a position slightly in front of and below the disk 18. Brush 51 is carried in spring clips 53 on the end 55 of lever 54 which is rotatably mounted on pin 55. The pin 55 is carried in bracket 56 which is riveted as shown at 57 to plate 58. To one end of the lever 54 is connected a spring 59, the other end of which is attached to a hook 60 carried by the plate 58. Juxtaposed to the spring 59 is a screw 61 which is threaded into a block 62 carried by hook 60. A spring 63 surrounds the shank of the screw 61 so as to prevent free rotation of the screw relative to the block 62. The

spring 59 causes the lever 54 to rotate about its pivot 55 so that the brush 51 will be moved upwardly through the aperture 52 into a position near the disk 18. The extent of the rotation of lever 54 is limited by the screw 63 which contacts with the end of the lever. A screw 64 is provided in the end of lever 54 which limits the extent of the rotation of the lever 54 in the direction opposite to that caused by spring 59. The plate 58 which carries brush 51 and its associated parts fits in an opening in table 50 and is removably held therein by latch 66 which cooperates with a ledge on the block 65 which is riveted to the plate 58. The latch 66 is mounted for rotation on the screw 67 extending into table 50. On rotation of the latch 66 about the pivot 67 from the position shown in Fig. 2 the plate 58 is released and may be lifted from the table 50 together with the brush 51 and its associated parts.

At 68, in Fig. 1, is indicated the base plate which is bolted to the base member 3. Base plate 68 carries, by web 69, the tubular member 70, which tubular member 70 forms a support for the cement disk casing and also serves as a drain for excess cement escaping from the disk 18 which cement is carried into the waste tank 701.

Frame 71 is fastened at the front side of member 70 by means of screws 72. Screws 74 serve to fasten plates 73 to the lower side of frame member 71. The plates 73 form together with the projecting portions 75 of the frame members 71 a pair of slots 76 in which slide 77 moves. The slide 77 is fastened to table 50 by means of bracket 78 and screws 79. The slide 77 carries rack 80 which operates with pinion 81 carried upon shaft 82 which has a manually operable knob 83 at its end. Operation of the knob 83 effects, through the rack and pinion, the adjustment of the table 50 relative to the cement disk 18.

After adjustment, the table is locked in position by means of a sleeve 87 threaded on to the shaft 82. Upon turning the sleeve 87 the shaft 82 is drawn to the left as shown in Fig. 2 whereupon conical head 84 on the end of shaft 82 is drawn into the recess 86 in the bracket 71. The frictional contact with the conical surface 85 of member 84 with the surface of the recess 86 locks the shaft 82 against rotation so that the table 50 will be held in its adjusted position.

In order to prevent the table 50 from being brought into too close proximity to the disk 18, a latch 88 is provided. Latch 88 is fastened by means of screw 89 to the slide 77 as shown in Fig. 4. The latch 88 has a projecting end operating in the notch 90 in plate 73. The projecting end of the latch 88 is held in position in notch 90 by means of spring 91 connected to the latch 125

and to the slide 77 as will be seen from Fig. 5. The motion of the table 50 is limited by the projecting end of latch 88 cooperating with the notch 90. The latch 88 has a bent over end 92 projecting below the lower end of the table 50 by which the projecting end of the latch 88 may be manually moved from engagement with the notch 90 so that the table may be removed, if necessary.

At the right side of the table 50, as shown in Fig. 2, there is positioned a brush 93, shown more particularly in Fig. 3. The brush 93 is held to the table 50 by bracket 95 riveted to table 50 and to which bracket the brush is clamped by the bolt and thumb screw 96.

Beneath the lower edge of the table 50 there is positioned a catch pan 97 which is removably mounted on the member 70 by means of brackets 98. The pan 97 serves to catch cement dripping from the lower edge of the table 50.

In the operation of the device the cement disk 18 is set into operation by belt 7 and pulley 8 and the connecting motion transmitting parts. Cement is fed from tank 25 onto the disk 18 through the valved conduit 24. As the cement flows into the disk housing 21 it covers the disk 18 on both sides. As the disk rotates, cement is carried out through aperture 34, the scraper 28 and dam 31 serving to direct the cement along the lower edge of the disk. The scraper 36 serves to divert the cement from the disk on to brushes 37 and 51. The shoe to be cemented is then placed upon the table 50 and its side is brought into contact with the disk 18 and brush 37 and, as the shoe is moved so that various portions of its side is brought into contact with the disk 18 and brush 37, cement is applied thereto. As the shoe is moved in contact with brush 37 and disk 18, the bottom and shank of the shoe are wiped over the brush 51 which brush is resiliently held in contact therewith by means of spring 59. After the cement has been applied to the shoe any excess cement which may be upon the bottom of the shoe is wiped off by wiping the bottom across the top of the brush 93 which is conveniently located at the edge of the table 50, the excess cement flowing down the table and into the pan 97.

The degree of pressure of the brushes 37 and 51 upon the shoe is controlled by the screw 41 and spring 48 and by screw 61 and spring 59, respectively. The distance between the bottom of the shoe and the bead of cement applied by disk 18 can be varied by adjusting the table 50 with respect to disk 18 by means of rack and pinion 80 and 81.

The brush 37 may be replaced by moving the stop plate 44 out of contact with the

end of screw 41 whereupon the spring 48 will turn the arm 39 about its pivot 40 so that the brush 37 and its spring clip 38 will be thrust out beyond the disc edge 18, in which position the brush can be conveniently removed and a new one inserted therefor.

The brush 51 may be replaced by removing the plate 58 from table 50 whereupon access may be had to the brush 51 and its spring clip 53.

While the preceding description in connection with the drawings discloses a preferred embodiment of the invention, it is not intended to limit the invention to such embodiment but only to limit the invention by the claims which follow.

Having thus described my invention, what I claim and desire to protect by Letters Patent is:

1. A cementing machine having, in combination, a support for a shoe, means for applying cement to the upper of a shoe, and means mounted on the support for applying cement to the bottom of a shoe.

2. A cementing machine having, in combination, a support for a shoe, means for applying cement to the upper of a shoe, and means removably mounted on the support for applying cement to the bottom of a shoe.

3. A cementing machine having, in combination, a support for a shoe, means for applying cement to the upper of a shoe, and means mounted on the support for applying cement to the bottom of a shoe, the last mentioned means being adjustable relatively to the support.

4. A cementing machine having in combination, means for applying cement to the lower side portion of a shoe upper, and means for spreading the cement uniformly over the area to which it is applied, said spreading means being resiliently held in operative position.

5. A cementing machine having in combination, means for supplying cement to a surface of an article being moved relative to the means at a point of juxtaposition of the article and means, and a second means movable into and out of operative relation with respect to the article for uniformly spreading the cement over the surface to which it is applied, and means for normally maintaining the second means in operative position.

6. A cementing machine having in combination, means for supplying cement to the juxtaposed surface of an article being moved relative thereto, a second means adjacent the supplying means and arranged to spread the cement over the area to which it is applied, and means for resiliently urging the second means against that surface of the article to which the cement is being supplied.

7. A cementing machine having in combination, means for applying cement to the juxtaposed surface of an article being moved relative thereto, a brush for spreading a cement over the surface to which it is applied, and resilient means for urging the brush into contact with the surface to which the cement is supplied.
8. In a cementing machine in combination, means for supplying cement, a rotating disk for conducting the cement to the surface of a juxtaposed article, said disk acting to mark off the area to which the cement is supplied, and means for spreading the cement over the surface to which it is supplied, and means for resiliently urging the spreading means against the surface of the article.
9. In a cementing machine in combination, means for supplying cement, a rotating disk for conducting the cement to the surface of a juxtaposed article, said disk acting to mark off the area to which the cement is supplied, a brush for spreading a cement over the surface to which it is supplied, and resilient means for urging the brush into contact with the surface to which the cement is supplied.

Signed at New Haven, county of New Haven, State of Conn. this 1st day of May, 1928.

HERBERT R. POLLEYS.
